SHEET METAL FLOOR

Frank R. Higley, Cleveland Heights, Ohio, assignor to Insulated Steel Construction Company, Cleveland, Ohio, a corporation of Ohio

Application November 6, 1933, Serial No. 696,753

4 Claims. (Cl. 189—34)

This invention relates to metal building panels adapted for employment in floors, roofs, or otherwise disposed generally in horizontal planes as distinguished from vertical or wall planes. The invention contemplates the assembly of such a floor panel from sheet metal units bent to such sectional characteristics and so related that when the assembly is completed it will have the sectional characteristic of a continuous repeated box section.

A particular object of the invention is to provide such a sectional characteristic wherein the upper or flooring panel has greater thickness and consequently greater strength than the lower or ceiling panel, so that the floor panel as a whole will have greater strength for its weight and thickness than it would otherwise have. A further and coextensive object is to provide such characteristics from units which in themselves may have uniform thickness and are adapted for convenient assembly and securement therein to form the floor. The general objects are to accomplish these ends in the most inexpensive and simple manner.

The exact nature of this invention together with further objects and advantages thereof will be apparent from the following description taken in connection with the accompanying drawings which are all perspective views of the end edge portions of the parts which they represent, Fig. 1 showing a completed floor section, Fig. 2 being an enlarged detail of a typical part thereof, and Fig. 3 being a further enlarged showing of one of the characteristic units employed.

With reference now to the drawing and first to Fig. 3 thereof, a typical unit is shown. The unit comprises a strip of sheet metal which may be of uniform thickness as indicated, rectangularly bent along two parallel longitudinal lines as at 1 and 2 to form three longitudinally extending members including an intermediate member 3 extending between and joining a pair of parallel laterally extending members 4 and 5. The unit thus has a section which may be considered as of Z characteristic.

The bends 1 and 2 are so located that the intermediate member 3 is narrower than either of the members 4 and 5, and that one of these outer members, as 4, is substantially narrower than the other, 5. Preferably the wider member 5 has nearly twice the width of the narrower member 4, as will appear.

The floor panel is made up principally of an assembly of a plurality of such units, each disposed with its wider member 5 uppermost, as shown in

Fig. 2, the assembly being made preferably as in succession from right to left in that figure.

Fig. 2 shows a complete unit A, together with its immediately related units B on its left and C and D on its right, each unit being indicated generally by such letter reference character below its intermediate member 3.

It will be observed that the wider, upper member 5a of the A unit extends beyond the intermediate members 3c and 3d of the next adjacent units C and D on the corresponding side, overlying the upper member 5c of the C unit and terminating slightly beyond the intermediate member 3d of the D unit. The member 4a of the A unit extends in the opposite direction, slightly beyond 15 the intermediate 3b of the B unit, where it underlies the lower member 4b of the B unit. The member 4a of the A unit overlies the edge part of the member 4c of the C unit.

A similar relation obtains for all of the typical units, as will be obvious from Fig. 2.

Thus the upper wider member 5 of each unit in part overlies the corresponding parts of the next two adjacent units in one direction (right, Fig. 2), and underlies the corresponding parts 25 of the next two adjacent units in the opposite direction (left, Fig. 2).

The characteristics of the typical section shown in Fig. 2 will be observed as a continuous repeated box section wherein the vertical members 3 of the units constitute web elements extending between an upper or flooring panel and a lower or ceiling panel.

The lower or ceiling panel is composed of the narrower members 4 of the units disposed in shingled relation with but slight overlap so that its mean thickness is but slightly greater than that of the member 4 of one unit.

Similarly the upper or flooring panel is composed of the wider members 5 of the units disposed in shingled relation with great overlap so that its mean thickness is slightly greater than twice that of the member 5 of one unit.

In both flooring and ceiling panels the members are secured together adjacent the web elements 3, where they overlap, preferably by welding, as indicated at 6, at intervals spaced longitudinally of the units. In the upper or flooring panel each welded connection will be noted as including three elements, one between two others.

It will be observed that the characteristics of the typical floor section thus formed, are an upper panel of substantially twice the mean thickness of the lower panel. Thus the neutral axis of the section as a whole will lie closely adjacent

the upper or flooring panel part thereof, so that the structure will have greater strength for its weight and for its thickness, than would otherwise be the case. It will be further observed that at 5 the same time the flooring panel will present an external surface substantially smooth, with variant only to the extent of the thickness of a single upper member 5.

At its lateral edges a floor assembly of typical 10 units may be finished off as indicated in Fig. 1.

At the right side edge a pair of special units Y and Z are employed. The Y unit is comparable with the typical units A to D. It has an intermediate or web member 3y, a lower or ceiling 15 panel member 4y, these parts being dimensioned as in the typical units. It has an upper or flooring member 5y of width substantially equal to its member 4y, to be disposed coextensive with the extreme edge of the member 5d of the last typical 20 unit D.

The other special unit Z for this side edge of the assembly is generally of L section including a ceiling panel 4z, a web member 3z and a lip 5z.

At the opposite side edge of the assembly, also, 25 two special units are employed. One of these units Z' is identical with the special unit Z but is disposed the other side up, as indicated. The other special unit X is simply a flat strip of width approximately that of the member 5 of the typical 30 unit, to be disposed as shown.

These special units are welded in the assembly where their parts overlie those of the typical units as will be apparent. Preferably the parts are so proportioned and arranged that at each side 35 edge of the assembly a lip will be provided as at 7, in the upper or flooring panel on one side and as at 8 in the lower or ceiling panel on the opposite side. These lips 7 and 8 are for the purpose of providing connection with adjacent similar assemblies. Obviously by suitable proportioning and arrangement of the parts they may be omitted if not desired.

What I claim is:

1. In a floor panel of the class described, a plurality of similar units, each unit comprising a length of sheet metal bent in opposite directions along parallel longitudinal lines to form three members each disposed in a separate plane, the 50 outer members being parallel and one of width substantially twice that of the other, said units being assembled with the free edge portion of the narrower parallel member of one unit overlapping the next adjacent unit in one direction, at the intermediate member of the latter, and with the free edge portion of its wider parallel member extending beyond the intermediate member of the next adjacent unit in the opposite direction, and overlapping the second adjacent unit in

said opposite direction, at the intermediate member of the latter.

2. A plurality of similar units in a floor panel assembly, each unit having a section of Z characteristic with substantially rectangular bends between its members, the units being disposed with their outer members in shingling relation, each unit having one of its outer members substantially wider than its other outer member and each unit being disposed with its wider outer member uppermost, whereby the assembly provides a floor panel having the characteristic of a continuous repeated box section, the intermediate members of the units comprising webs vertically extending between spaced flooring and ceiling panels, 15 said flooring panel having a greater mean thickness than said ceiling panel by virtue of the greater width of the said members disposed in the flooring panel.

3. A plurality of similar units in a floor panel assembly, each unit having a section of Z characteristic with substantially rectangular bends between its members, the units being disposed with their outer members in shingling relation, each unit having one of its outer members substantially twice wider than its other outer member and each unit being disposed with its wider outer member uppermost, whereby the assembly provides a floor panel having the characteristic of a continuous repeated box section, the intermediate members of the units comprising webs vertically extending between spaced flooring and ceiling panels, in the flooring panel the overlap of said shingling members providing a minimum of two thicknesses thereof and in the ceiling panel the overlap of said shingling members therein providing maximum of two thicknesses thereof.

4. A plurality of similar units in a floor panel assembly, each unit having a section of Z characteristic with substantially rectangular bends between its members, the units being disposed with their outer members in shingling relation, each unit having one of its outer members substantially twice wider than its other outer member and each unit being disposed with its wider outer member uppermost, whereby the assembly provides a floor panel having the characteristic of a continuous repeated box section, the intermediate members of the units comprising webs vertically extending between spaced flooring and ceiling panels, in the flooring panel the overlap of said shingling members providing a minimum of two thicknesses thereof and in the ceiling panel the overlap of said shingling members therein providing maximum of two thicknesses thereof.

FRANK R. HIGLEY.
